DYNAMOELECTRIC MACHINE

Vincent J. Picozzi, Scotia, Earl K. Stewart, Ballston Lake,
and Howard C. Ward, Jr., Schenectady, N.Y., assignors
to General Electric Company, a corporation of New
York

Filed Sept. 25, 1961, Ser. No. 66,827

Term of patent 14 years

(Cl. D26—5)

FIG. 1

FIGURE 1 is a perspective view illustrating the front and side portions of a dynamoelectric machine embodying the new design; and

FIGURE 2 is a perspective view similar to FIGURE 1 and illustrating the back and side portions of the machine.

We claim:

The ornamental design for a dynamoelectric machine, as shown.
